FIG. 11

FIG. 12

FIG. 13

FIG. 14

FIG. 15

FIG. 16

FIG. 1 is a perspective view of an anti-skid chain link embodying my new design;

FIG. 2 is a side elevational view thereof;

FIG. 3 is an end elevational view thereof;

FIG. 4 is a bottom plan view thereof;

FIG. 5 is a perspective view of a modified form of the anti-skid chain link shown in FIG. 1;

FIG. 6 is a side elevational view of FIG. 5;

FIG. 7 is an end elevation view of FIG. 5;

FIG. 8 is a bottom plan view of FIG. 5;

FIG. 9 is a perspective view of another modified form of the anti-skid chain link shown in FIG. 1;

FIG. 10 is a side elevational view of FIG. 9;

FIG. 11 is an end elevational view of FIG. 9;

FIG. 12 is a bottom plan view of FIG. 9;

FIG. 13 is a perspective view of a further modified form of the anti-skid chain link shown in FIG. 1;

FIG. 14 is a side elevational view of FIG. 13;

FIG. 15 is an end elevational view of FIG. 13; and

FIG. 16 is a bottom plan view of FIG. 13.

I claim:

The ornamental design for an anti-skid chain link, as shown and described.
